UNITED STATES PATENT OFFICE

2,252,979

REFRIGERATION APPARATUS

Alexander L. Reiter and Leonard P. Traxel, Chicago, Ill., assignors to Mills Novelty Company, Chicago, Ill., a corporation of Illinois

Application October 21, 1937, Serial No. 170,136

13 Claims. (Cl. 62—115)

This invention relates to refrigerating systems and more particularly to that type of refrigerating system which must be adaptable to handle widely varying heat loads, such as, for example, a refrigerating system used in connection with a merchandise-vending machine which is allowed to stand for long periods of time while its contained articles of merchandise are gradually dispensed one by one, and then, when nearly empty, is refilled with uncooled articles, imposing a sudden load upon it that is much higher than its normal load after the articles have been cooled to the normal operating temperature of the machine.

The invention is applicable to refrigerated vending machines for vending bottled beverages, packaged goods, and the like, which are placed in the machine and dispensed under the conditions above indicated.

It is important that the peak load on the evaporator coils be absorbed as quickly as possible in order to prevent temperature rise in the refrigerator.

In a refrigerated vending machine, peak loads come at infrequent intervals of two or three times a day. After this load has been removed, the refrigerating demand is comparatively small, being only that required to compensate for loss of heat from the machine. There will be no frequent opening and closing of the door to the merchandise compartment as in the case of a domestic or butcher's refrigerator, and accordingly, the heat loss in the interim between peak loads will be much less than in the ordinary refrigerator. The present invention aims, therefore, to provide a refrigerating system particularly adapted to meet a condition wherein the ratio between peak load and normal demand is unusually high. Since a system large enough to handle a peak load is inefficient in the handling of a normal load, it is important that provision be made for varying the refrigerating capacity of the system in accordance with the demand; and the present invention provides mechanism designed to achieve such variation in capacity over wide fluctuations of demand.

Another object of the invention is to provide an arrangement in which the refrigerating capacity may be boosted to a maximum immediately when the peak demand arises, and in which the refrigerating effect is quickly lowered to normal when the peak load has been removed.

These objects are accomplished, in general, by the provision of two independently-functioning refrigerating elements, including a primary

evaporator for normal-demand operation and a secondary evaporator for peak-load operation. It has been proposed to meet fluctuating demand by arranging two evaporators in series with each other, such arrangement avoiding certain difficulties which arise where attempt is made to employ two evaporators in parallel. But a series arrangement of evaporators is found to be unsuitable for the efficient handling of loads varying as widely as in a refrigerated vending machine. The present invention proposes, therefore, to utilize a parallel arrangement of evaporators.

The difficulties attendant upon the employment of a parallel relationship are solved in the present invention, and the other objects hereinbefore stated are in general attained by arranging for only one of the evaporators to be operative at any given time. Accordingly, means are provided for shutting off one evaporator when the other is in circuit with the compressor, and vice versa. It will be understood in this connection, of course, that a basic requirement is that a single compressor, common to both refrigerating circuits, be employed.

Another important feature in attaining the desired ends is the provision of a hold-over medium (a liquid adapted to congeal during a period of normal demand and to utilize its latent heat-absorbing capacity during peak-load operation). The hold-over medium is associated with the primary evaporator which handles the normal-demand operation, and cooperates with the secondary evaporator during peak-load operation. The secondary coil is constructed and arranged so as to have a high heat-transfer capacity per se, so that the combined refrigerating capacity of the hold-over medium and the secondary evaporator is very high.

Another object of the invention is to provide an arrangement in which defrosting will be effected without shutting down the machine, and without raising the temperature within the machine above the temperature limits of normal operation.

In conventional refrigerating systems, it is customary to effect defrosting by permitting a temperature rise above the normal temperature limits of the refrigerated space. The present invention accomplishes defrosting without exceeding the normal limits of the machine, first by adopting a temperature range just above the freezing point of water (both maximum and minimum limits being above 32° Fahrenheit), by employing water as the hold-over medium,

and by the aforesaid arrangement whereby only one evaporator at a time is in operation. The invention in this respect embodies the discovery that the hold-over casing will, when the primary evaporator is cut out, assume an exterior temperature that is sufficiently higher than that of the ice it contains (which, of course, will at a maximum, be 32° Fahrenheit) so that the frost on its exterior surface will melt. This temperature, while ice remains in the hold-over casing, will approximate 33° Fahrenheit.

The invention further accomplishes the change-over from one evaporator to the other, without the use of a two-way valve.

The last two mentioned objects are accomplished by employing a resistance valve in the line leading to the auxiliary evaporator, which valve normally shunts the refrigerant flow through the primary evaporator, and employing a control valve for cutting off the flow to the latter, whereby the flow will be forced to travel through the auxiliary evaporator. The resistance valve also serves to reduce the operating pressure in the auxiliary evaporator below that in the primary evaporator, so that the operating temperature of the auxiliary evaporator may be lower than that of the primary evaporator.

Another object of the invention is to provide means for maintaining a constant supply of water in the hold-over casing, without employing an external source of supply. To this end, the condensate from the auxiliary evaporator, and the water produced by the defrosting of said evaporator, is led into the hold-over casing. We find that this provides an adequate supply so that the hold-over casing is automatically kept full, without attention on the part of the operator.

A further object is to provide a novel refrigerating element comprising a flat coil and a narrow casing or tank in which the coil is embedded in a hold-over liquid contained therein, the arrangement being such that the casing will be unaffected by freezing of its contained water, and maximum efficiency of heat transfer will be had. This object may be accomplished by employing a casing that has side walls diverging upwardly, embedding the lower bends of the coil in a substance that is solid at all temperatures to which the coil may be subjected, and soldering the reaches of the coil to one side of the casing, or by applying the coil to the exterior of the sidewall, or by extending the return bends beyond the bottom of the casing.

Other objects and advantages of the invention will become apparent from the following detailed description, which, taken in connection with the accompanying drawings, discloses a preferred embodiment thereof.

Referring to the drawings:

Figure 1 is a diagrammatical view of a refrigerator embodying the invention;

Figure 2 is a partial vertical, sectional view through such refrigerator;

Figure 3 is a detailed sectional view of the primary heat transfer unit;

Figure 4 is a detailed sectional view of a portion of the same;

Figure 5 is a detailed sectional view of a portion of a modification of the heat transfer unit;

Figure 6 is a detailed sectional view of the control valve; and

Figure 7 is a view similar to Figure 1, showing a modification of the invention.

Referring first to Figure 2, a bottle-dispensing machine constructed in accordance with the in-

vention comprises a cabinet including a front wall 10, a rear wall 11, a bottom wall 12, side walls 13, and a top 14 in which the refrigerant compressing and air-circulating mechanism is contained. Each of the aforesaid walls incorporates insulating material so as to provide an enclosure in which refrigerated air may be circulated with a minimum of heat loss.

This enclosure is divided into a merchandise storage and dispensing chamber 15 and an air return passage 16, a refrigerating element assembly, designated generally at 17, serving as a partition between these areas. The refrigerating element assembly 17 includes a wall 18 of sheet metal or the like, extending the full width of the space between the side walls 13 of the cabinet, a wall 19 upwardly bent from the lower end of the wall 18 on the rear side thereof and forming therewith a hold-over casing 20, and evaporating coils 21 and 22 disposed, respectively, in and above the hold-over casing 20.

From the upper end of the wall 18, a wall 23 extends to the front wall 10 of the cabinet and from one to the other of the side walls 13. Attached to the wall 23 and communicating with an opening 24 therein, is a blower casing 25 in which is rotatably mounted a blower impeller 26. The blower 25, 26 pulls air from the horizontal space 27 extending laterally from the upper end of return passage 16 and formed between the top 14, the wall 23, and the side walls 13, and blows it through the opening 24 into the merchandise storage and vending compartment 15. From the compartment 15, the air travels through a space 28 between the lower end of the casing 20 and the bottom wall 12, into the return passage 16.

As the air passes through the compartment 15, it will absorb heat from the bottles 29 carried therein by the endless carrier 30. The conveyor and dispensing mechanism are preferably as shown in United States Patent No. 2,189,740, issued February 6, 1940. As it travels downwardly, the air will give up some of this heat to the wall 18, and as it passes upwardly through the return passage 16, it will be further cooled by the wall 19.

The element 21 is welded or soldered directly to the wall 19 so that heat will be readily conducted through the wall 19 to said element 21. The casing 20, which, in effect, forms a very thin, deep tank, is filled with water 31 which acts as a hold-over liquid and which also serves to conduct heat from the wall 18 to the evaporator 21 during normal operation.

The compressor 32 is shown diagrammatically in Figure 1. From its high side, the compressed refrigerant is conveyed through the conventional condenser coil 33 into a receiver 34 from which it passes through the feed tube 35 to an expansion valve 36 and thence to a T union 37. From the T union 37, tubes 38 and 39 lead to the evaporators 21 and 22, respectively. From the evaporators 21 and 22, tubes 40 and 41, respectively, lead to a T union 42, from which a return or vapor tube 44 leads back to the compressor.

It will thus be seen that two parallel evaporator circuits are provided, a primary circuit including the compressing and condensing mechanism 32, 33, 34, the tube 35, the expansion valve 36, the line 38, the primary evaporator 21, the tube 40, and the return tube 44 leading back to the compressor, and the other circuit comprising the compressing and condensing mechanism 32, 33, 34, the tube 35, the expansion valve 36, the

tube 39, the secondary evaporator 22, the tube 41, and the return tube 44.

A resistance valve 43 is interposed in the tube 39 leading to the secondary evaporator 22. This valve offers a resistance to opening which is sufficient to maintain it closed against the pressure normally existing in the system when the primary circuit is open.

A control valve 45 is inserted in the line 40 in the primary circuit and functions, when opened, to open the primary circuit and allow refrigerant to circulate through the evaporator 21 for normal operation. The operator may manually close the valve 45 when he refills the machine. The closing of the valve cuts off communication between the lines 40 and 44, thus shutting off the primary circuit, and causing the secondary circuit to open. The compressor, overcoming the resistance of valve 43, will then send the refrigerant through the evaporator 22 instead of the evaporator 21, and the refrigerant in the primary evaporator will boil off through the valve 43 into the secondary evaporator. The water 31 in the hold-over casing, which has been frozen to ice by the preceding extended period of normal operation, will thence commence to absorb the heat load which has been imposed upon the machine by the fresh charge of bottles. The air will, after having been preliminarily cooled by the hold-over casing, pass over the secondary refrigerating element which comprises an open coil of many turns, and will be further cooled thereby. As the peak load is gradually absorbed, the ice in the hold-over casing will melt and utilize its latent heat-absorbing capacity.

Before the ice has completely melted, the temperature within the enclosure will, under normal conditions, be reduced to 33° Fahrenheit, which is the lower limit of the operating range of the machine. At this temperature, the compressor will be shut off by the opening of compressor control switch 10, which in turn is controlled through a tube 71, by a thermostatic bulb 72 located in the dispensing compartment 18 near the bottle-delivery opening 13 in the front wall 10 of the machine (the warmest region of the machine during the idling period of the refrigerating mechanism).

After the compressor has ceased operating, the temperature in the machine will again begin to rise, until it approaches the upper limit of the operating range, which preferably is in the neighborhood of 38°. Before it reaches this limit, however, the pressure in the refrigerant circulating system will have increased to such an extent that the control valve, which is constructed to react to such pressure increase, as will herein-after be more fully set forth, if it is not locked in closed position, will open, so as to open the primary circuit and allow the secondary circuit to close.

The system will then be ready for another cycle of normal operation, and when the upper temperature limit is reached, the thermostatic switch 70 will close and complete the electric circuit 14 which supplies power to the compressor motor 15, and the compressor will commence to circulate the refrigerant through the evaporator 21.

The primary evaporator will then again begin to abstract heat from the hold-over water 31, and the latter will in turn abstract heat through the casing 20 from the circulating air. When the air has been cooled to a temperature at

which it can no longer give up sufficient heat to the hold-over casing 20 to keep the hold-over water 31 at a temperature above freezing, the latter will commence to congeal. When fully frozen, it will under normal conditions allow the temperature of the circulating air to drop to the lower limit of the operating range, whereupon the switch 70 will again open, shutting off the compressor. Should this happen, a subsequent raise to the upper limit of the operating range, will have no effect on the control valve 45 since the latter will be already open, but will simply cause the compressor to again go into operation.

The control valve 45 (Figure 6) comprises a casing 46 in which is housed a bellows 47 positioned above a hollow cylindrical neck portion 48 at the lower end of which is formed a nipple 49 connected to the line 40 of the primary circuit. A nipple 50, higher up on the cylinder 48 is connected to the T union 42. A valve seat 51 is formed between the nipples 49 and 50. A valve element 52, having a guide skirt 53 slidably mounted in the cylinder 48, is adapted to seat against the valve seat 51. An arrowhead member 55 on the end of the plunger 54 having upper and lower conical surfaces 55a and 55b, respectively, engages between rollers 56 mounted on spring arms 57 attached to the skirt 53. The head 58 of the bellows 47 is rigidly attached to the plunger 54, and a coil spring 59, engaged between the cap 60 of the casing 46 and the head 58, urges the plunger in a downward direction when the valve is positioned as in Fig. 6. The plunger 54 has a button 54a on the outer end thereof adapted to be engaged by a hinged wire 54b, the ends of which, indicated by the reference numerals 54c, are turned inwardly and pass through openings (not shown) in the casing 46, to provide a hinged connection therewith. A transverse outer portion 54d has a crimp 54e therein, adapted to enter a depression (not shown) in the button 54a to hold said parts in interlocked relation for such period as it may be desired to lock the valve 52 in closed position.

By pushing in the plunger 54, the valve element 52 is caused to seat against the valve seat 51 as a result of the rollers 56 riding against the upper conical surface 55a. The spring arms 57 urge the rollers 56 toward each other and in seeking to embrace the narrowest portion of the head 55, the rollers 56 will, when riding against the upper conical surface 55a, lift the valve relative to the plunger, while when riding against the lower conical surface 55b, the rollers 56 will cause the valve to move downwardly relative to the plunger. Pushing in the plunger 54 when the valve is open causes the head 55 to force its way between the rollers until the latter have passed the major diameter of the head 55 whereupon the rollers will react with the upper conical surface to move the valve upwardly relative to the plunger.

As above indicated, the valve may be held closed for so long as desired by means of the locking wire 54b, the purpose of so locking it in closed position being ordinarily to provide for removal of any excessive frost in and about the primary evaporator 21, in case the heat introduced when the door of the machine is open for refilling is not sufficient for effecting satisfactory defrosting. Normally the wire 54b is allowed to hang at the side of the casing 46, and is primarily for the purpose of facilitating defrosting in the manner above described, although it ob-

viously may be used at any time when it is desired to cut out the primary evaporator. It is accessible to the operator when the door of the machine is open, and when the conditions are such that it is no longer desired to lock the valve closed, said wire may be removed from engagement with the button 54^a, leaving the valve free to be opened by the bellows 47.

The pressure in the system is communicated to the bellows 47 through the cylinder 48 (the skirt 53 allowing the gas to pass). When the critical temperature is reached, the pressure will have overcome the resistance of the spring 59 to such an extent that the plunger 54 will have arrived at a position in which the major diameter of the head 55 will have passed between the rollers in an upward direction whereupon the rollers 56 will ride downwardly against the surface 55b to move the valve element 52 away from the seat 51, thus opening the control valve 45 and causing the resistance valve 43 to close.

The control valve 45 is designed for manual operation so that the operator may immediately close the valve when he opens the machine. However, the invention also contemplates fully automatic operation in which, as shown in Figure 7, the valve 45 is closed thermostatically by a thermostatic control element 76 located in the upper region of the storage and dispensing compartment and adapted to exert through the line 77 sufficient pressure against the top of the bellows 47 so as to overcome the pressure within the bellows, when a peak load is imposed upon the system, to such an extent as to cause the valve to close. It will be understood that for this purpose a pressure sensitive element might be placed adjacent the top of the bellows in place of the plunger 54 and in communication with a temperature-controlled pressure medium contained in the line 77.

One manner in which this may be accomplished is to allow an interval of time to occur between the cutting in of the compressor and the change-over from the primary to the secondary evaporator. Normally the pressure at which the bellows 47 will cause the control valve to close, is approximately 20 pounds. With the temperature in the enclosure at 33°, and the evaporating coils having remained inactive over a period of time normally necessary for the temperature to have raised from 33° to 38°, the temperature within the evaporators will be sufficiently high so as to produce in the neighborhood of 20 to 22 pounds pressure therein.

However, after the compressor has been cut in, the temperature within the evaporators will rapidly drop so as to pull down the pressure to the normal operating pressure of about 9 pounds, while the temperature within the enclosure still remains in the neighborhood of 38° or more under the fresh charge of warm bottles. The control element 76, located preferably in the region most heated by the warm bottles (in the upper region of the bottle storage and dispensing compartment), will react therefore to a temperature that remains high while the temperature in the evaporators is rapidly dropping, and will create a pressure which may range upwardly of 20 pounds, which will be amply sufficient to overcome the pressure within the bellows at some point prior to the time when the latter drops back to the normal operating pressure of 9 pounds.

The operation of the automatic control may be made practically simultaneous with the re-

loading of the machine by arranging the mechanism so that the temperature above the warm bottles may reach 40 to 42° (2 to 4° above the temperature at which the compressor cuts in) whereby the thermostat 76 may overcome the pressure within the bellows 47 while the latter still remains in the vicinity of the 20 pounds at which the valve opens. In any event, the operation of the valve in both directions is assured by the fact that the valve opens during a period when the compressor is not in operation and when it is possible for the temperature within the evaporators to approach that of the air in the enclosure, whereas the valve is closed at a time when the compressor is operating, causing the temperature within the evaporators to be pulled down so as to remove the high pressure from within the bellows.

One of the requirements in a machine of this kind is that the bottles be kept dry. This is accomplished by locating the refrigerating unit in the return passageway 18 and allowing the condensate which collects on the hold-over casing to drip from the lower edge thereof directly onto the bottom 12 from which it may be collected by suitable collecting means. The condensate from the secondary evaporator 22 is usefully employed for the purpose of replenishing the hold-over water in the casing 20. To this end, a drip pan 65 is provided below the evaporator 22 and is provided with a drain pipe 66 which drains into the open, upper end of the casing 20.

Another problem solved by the present invention is that of avoiding bursting of the hold-over casing by the freezing of the water therein. This involves, first, diverging of the walls 18 and 19 upwardly, and, second, the filling in of the bottom of the casing with a solid material which will hold its position, such as wax or some type of cement. This filling material is indicated in Figure 1 at 67. It covers the lower bends 68 of the evaporator coil 21 so as to avoid the occurrence of the condition illustrated in Figure 4. Where the water fills the casing to the bottom thereof, the gradual building up of ice layers along the bends of the coil 21 will ultimately result in the imprisonment of a wedge-shaped region of water 69. The subsequent freezing of this region 69 will cause a tank to bulge and ultimately to burst.

The filling in of the bottom of the tank above the level of the bends 68, causes the ice to form only in vertical layers, so that there is no opportunity for water pockets to form. The same result can be achieved by extending the tubes 21 through the bottom of the tank 20, as shown in Fig. 7; or by attaching the reaches of the coil to the outside of said tank, as shown in Fig. 5. An added advantage is possible in this arrangement; namely, the use of an extended heat transfer surface 78, which serves to carry heat to the hold-over medium much more rapidly than is possible through the medium of just the walls of the hold-over casing.

While it is necessary for the pressure in the line 35 to raise slightly above the normal operating pressure in the primary circuit in order to open the valve 43, the pressure drop through the valve 43 is sufficient so that the refrigerant will circulate through the secondary circuit at a pressure considerably less than that in the primary circuit. Thus the secondary refrigerating element operates at a lower temperature than the primary refrigerating element, and air coming off the primary element, even though cooled to

the temperature of the primary element, will be further cooled by passing over the secondary element.

While the thermostat 16 is set to cut out the compressor at 33°, the temperature of the refrigerating units will drop below this level, which is determined in the warmest region—i. e., near the discharge opening. Accordingly, the refrigerating elements will become frosted while they are in operation. However, during normal operation, the secondary evaporator will raise to a temperature above 32° Fahrenheit, and will thereby become defrosted. Likewise, during peak-load operation, the temperature of the surfaces of the hold-over casing 20 will warm up to about 33°, even while ice remains in the casing, so that these surfaces will be defrosted also during each cycle of operation.

The expansion valve 36 may be of a thermostatic type, controlled by a thermostatic bulb 80, acting through a tube 81, as shown in Figure 7. The bulb 80 will be arranged to react to mean temperatures of the two evaporators 21 and 22, being connected in thermal contact therewith by a clip 82.

In the modification shown in Figure 7, a check valve 84 is incorporated in the intake tube 38 of the primary evaporator 21. The purpose of this valve is to prevent the escape of refrigerant from the primary evaporator when the latter is cut off by the control valve 45 and the secondary evaporator 22 is in operation. By completely closing off both the inlet and the outlet of the evaporator 21, and thus maintaining the latter full of refrigerant, the efficiency of the evaporator in transferring heat from the extended surface 78 into the hold-over 31, is materially increased. The refrigerant in the lower regions of the evaporator, vaporizing under the effect of the heat being absorbed through the extended surface 78, will rise into the upper regions of the evaporator, where it will be condensed by the loss of heat into the hold-over and, becoming a liquid, will move downwardly to displace the vaporized refrigerant rising from the lower regions. The tendency of the refrigerant to completely vaporize as the temperature in the hold-over raises above the boiling point of the refrigerant under normal pressures, will be retarded by the increase in pressure developed in the evaporator by the imprisoned vapor so that a certain amount of circulation of the refrigerant will continue to take place even as the temperature of the hold-over approaches the melting point.

In the showing of the modified form in Figure 55, the compressor and its associated members are illustrated only roughly by the rectangle 32a.

The upper evaporator 22 preferably incorporates an extended heat transfer surface 83, as indicated in both Figures 1 and 7.

The foregoing detailed description has been given for clearness of illustration only, and no unnecessary limitations should be understood therefrom, but the appended claims should be construed as broadly as permissible in view of the prior art.

We claim as our invention:

1. In a refrigerating system, an enclosure to be refrigerated, a compressor; a primary refrigerant circuit, including said compressor, a primary evaporator, and a control valve for opening and closing said circuit; a secondary circuit, including said compressor, a secondary evaporator and a resistance valve adapted to close said secondary circuit when said primary circuit is

open and to open under predetermined pressure built up by the closing of the primary circuit and to thereupon open said secondary circuit; and a hold-over medium in heat transfer association with said primary evaporator including a liquid adapted to congeal when said primary evaporator is in operation and to cooperate with the secondary evaporator in handling peak loads when said primary evaporator is not operating.

2. In a refrigerating system, an enclosure to be refrigerated; a compressor; a primary refrigerant circuit, including said compressor, a primary evaporator, and a control valve for opening and closing said circuit; a secondary circuit, including said compressor, a secondary evaporator and a resistance valve adapted to close said secondary circuit when said primary circuit is open and to open under pressure built up by the closing of the primary circuit and to thereupon open said secondary circuit; and means responsive to pressure built up in the system as a result of vaporization during a period of inactivity of said compressor for causing said control valve to open so as to open said primary circuit.

3. In a refrigerating system, an enclosure to be refrigerated; a compressor; a primary refrigerant circuit, including said compressor, a primary evaporator, and a control valve for opening and closing said circuit; a secondary circuit, including said compressor, a secondary evaporator and a resistance valve adapted to close said secondary circuit when said primary circuit is open and to open under pressure built up by the closing of the primary circuit and to thereupon open said secondary circuit; thermostatic means responsive to temperatures in the enclosure for starting and stopping said compressor, and means responsive to pressure built up in the system after a period of inactivity of said compressor for causing said control valve to open so as to open said primary circuit.

4. In a refrigerating system, a compressor, primary and secondary refrigerant circuits, each including said compressor and an evaporator, said circuits being in parallel with each other, means for controlling said circuits so that one and only one thereof will be open at any given time, thermostatic means responsive to temperatures in the enclosure for starting and stopping said compressor, and means responsive to predetermined pressure built up in the system after a period of inactivity of said compressor for causing said circuit controlling means to open the primary circuit and close the secondary circuit.

5. In a refrigerating system, a compressor, primary and secondary refrigerant circuits, each including said compressor and an evaporator, said circuits being in parallel with each other, means for controlling said circuits so that one and only one thereof will be open at any given time, thermostatic means responsive to temperatures in the enclosure for starting and stopping said compressor, means responsive to pressure built up in the system after a period of inactivity of said compressor for causing said circuit controlling means to open the primary circuit and close the secondary circuit, and thermostatic means for closing said control valve at the beginning of a period of peak-load operation.

6. In a refrigerating system, a compressor, primary and secondary refrigerant circuits, each including said compressor and an evaporator, said circuits being in parallel with each other, means for controlling said circuits so that one and only one thereof will be open at any given

time, thermostatic means responsive to temperatures in the enclosure for starting and stopping said compressor, means responsive to pressure built up in the system after a period of inactivity of said compressor for causing said circuit controlling means to open the primary circuit and close the secondary circuit, and manually operable means for closing said control valve at the beginning of a period of peak-load operation.

7. In a refrigerating system, an enclosure to be refrigerated; a compressor; a primary refrigerant circuit, including said compressor, a primary evaporator, and a control valve for opening and closing said circuit; a secondary circuit, including said compressor, a secondary evaporator and a resistance valve adapted to close said secondary circuit when said primary circuit is open and to open under pressure built up by closing of the primary circuit and to thereupon open said secondary circuit, said control valve being adapted to reopen under pressure built up in the primary circuit by the raising of the temperature therein above a predetermined limit; and a hold-over medium in heat transfer association with said primary evaporator adapted to congeal when said primary evaporator is in operation and to cooperate with the secondary evaporator in handling peak loads when said primary evaporator is inoperative.

8. In a refrigerating system, an enclosure to be refrigerated; a compressor; a primary refrigerant circuit, including said compressor, a primary evaporator, and a control valve for opening and closing said circuit; a secondary circuit, including said compressor, a secondary evaporator and a resistance valve adapted to close said secondary circuit when said primary circuit is open and to open under pressure built up by the closing of the primary circuit and to thereupon open said secondary circuit; thermostatic means responsive to temperatures in the enclosure at maximum and minimum limits for respectively starting and stopping said compressor; means responsive to pressure built up in the system as a result of the raising of the temperature in the enclosure to a level beneath the maximum limit for causing said control valve to open so as to open said primary circuit; and a hold-over medium in heat transfer association with said primary evaporator adapted to congeal when said primary evaporator is in operation and to cooperate with the secondary evaporator in handling peak loads when said primary evaporator is inoperative.

9. In a refrigerating system, an enclosure to be refrigerated; a compressor; a primary refrigerant circuit, including said compressor, a primary evaporator, and a control valve for opening and closing said circuit; a secondary circuit, including said compressor, a secondary evaporator and a resistance valve adapted to close said secondary circuit when said primary circuit is open and to open under pressure built up by the closing of the primary circuit and to thereupon open said secondary circuit; thermostatic means responsive to temperatures in the enclosure at

maximum and minimum limits for respectively starting and stopping said compressor; and means responsive to pressure in the system at a temperature intermediate said limits, for causing said control valve to open so as to open said primary circuit.

10. In a refrigerating system, an enclosure to be refrigerated; a compressor, a primary refrigerant circuit, including said compressor, a primary evaporator, and a control valve for opening and closing said circuit; a secondary circuit, including said compressor, a secondary evaporator and a resistance valve adapted to close said secondary circuit when said primary circuit is open and to open under pressure built up by the closing of the primary circuit and to thereupon open said secondary circuit; thermostatic means responsive to temperatures in the enclosure at maximum and minimum limits for respectively starting and stopping said compressor; means responsive to pressure in the system at a temperature intermediate said limits for causing said control valve to open so as to open said primary circuit; and thermostatic means for causing said control valve to close when a peak load is imposed upon the system.

11. In a refrigerating apparatus for a bottle vending machine, a cabinet having an interior space forming a bottle storage compartment and a return air passage, each extending from top to bottom of said space, a refrigerating element forming the dividing wall between said passage and compartment, and air circulating means disposed in the cabinet above said space for causing air to travel downwardly through said bottle compartment to be initially cooled by contact with said refrigerating element during said downward travel, to thence pass upwardly through said passage, to be finally cooled therein, and to then return to said bottle storage compartment, said element extending from side to side and to the top of said space and being spaced from the bottom of the cabinet to form an opening through which air may pass from said compartment into said passage, but arranged so as to discharge its collected condensate directly upon said bottom.

12. In a refrigeration system, a refrigerating evaporator comprising a coil of tubing having vertically disposed portions and return bends joining the lower ends of said portions, a tank of water in which said coil is immersed, said bends being near the bottom of the tank, and means excluding the water from the region of said bends.

13. In a refrigeration system, a pair of refrigerating evaporators, one above the other, a tank of hold-over water in which the lower evaporator is immersed, and means for replenishing said water-comprising means for collecting condensate from the upper evaporator and draining the same into the lower evaporator.
